UNITED STATES PATENT OFFICE.

RICHARD M. COMISKEY, OF QUINCY, ILLINOIS.

CYLINDER.

Application filed November 25, 1922. Serial No. 603,276.

To all whom it may concern:

Be it known that I, RICHARD M. COMISKEY, a citizen of the United States, residing at Quincy, in the county of Adams and State 5 of Illinois, have invented new and useful Improvements in Cylinders, of which the following is a specification.

An object of this invention is to produce a cylinder for clothes washing machines of 10 a construction to insure the thorough saturation and agitation of the clothes arranged therein when the cylinder is positioned in the machine and subjected to an oscillatory movement in a rotary direction, and whereby 15 the clothes will be effectively washed in an expeditious manner without liability of damage thereto.

To the attainment of the foregoing and other objects which will present themselves 20 as the nature of the invention is better understood, reference is to be had to the drawings which accompany and which form part of this application.

In the drawings:—

25 Figure 1 is a front elevation of the improved cylinder.

Figure 2 is a top plan view thereof.

Figure 3 is a sectional view on the line 3—3 of Figure 2.

30 Figure 4 is a sectional view on the line 4—4 of Figure 2.

Figure 5 is a sectional view on the line 5—5 of Figure 2.

35 Figure 6 is a sectional view on the line 6—6 of Figure 5.

The clothes receiving cylinder, forming the subject matter of the present invention is designed for either continuous rotary movement, a partial rotary movement in one 40 direction and a similar rotary movement in another direction, or a continuous oscillatory movement in a rotary direction. The ends 1 of the cylinder are in the nature of disks, being preferably formed of wood, the said 45 ends having their central portions provided with reduced extensions which are round in plan, and the said extensions are centrally provided with short shafts or trunnions 2 received in the usual bearings in a washing 50 machine (not shown).

The cylindrical body of the improvement is also preferably formed of wood, and surrounding the edges of the body there are metal bands 3 secured to the body, the said 55 securing means also entering the ends 1. At its top the body is provided with an opening

for a cover 4, which is arcuate in cross section. Metal bands are preferably secured at the ends of the cover, the same having one of their ends lipped as at 5, and their other ends provided with barrels to engage between similar barrels on straps 6, the said straps being secured to the body. Suitable pivots pass through the barrels. Slidable in 60 depressions in the cover below the straps 6 and adjacent the lipped ends thereof are catch elements 7 that are also designed to engage beneath the bands 3 on the ends of the body. The catch members 7 are preferably in the nature of flat spring plates on 65 which are centrally formed handles 9. The rear portions of the said catch members are normally covered by plates which partly 70 close depressions in which the catches are received.

The body has its bottom portion centrally provided with spaced apertures 10, and the inner face of the bottom has arranged therein a cup-like member 11 that surrounds the apertures 10. The cup member has a central 75 securing element 13 passing therethrough which, of course, enters the bottom 14 of the body, and the said cup member is provided with spaced apertures 15. At its edges, the bottom 14 of the body has connected thereto 80 inwardly inclined wooden strips 16, which have a central line of apertures 17. Secured adjacent to the inner ends of the strips 16 are outwardly inclined strips 18 which are not provided with openings. The strips 18 85 are connected to the lower edges of the sides 19 of the body, and the said sides 19 have preferably staggered apertures 20 therethrough. The sides 19 have their upper edges connected to inwardly inclined strips 21, similar 90 to the strips 18, and adjacent to the ends of the said strips 21 there are secured angularly disposed strips 22, similar to the strips 16. The strips 22 are provided with a central line of spaced apertures 23, and the 95 said pairs of strips 21 and 22 also provide the body with inwardly extending ribs.

The inner edges of the strips 16 and 22 project a suitable distance beyond the inner faces of the strips 18 and 21, and these projecting portions are rounded, as at 24 and 100 are provided with angular notches 25. It is to be noted that the notches 25 on the adjacent rounded inner edges 24 of the strips 22 and 26 are arranged at reverse angles, the 105 object being that water or clothes thereagainst will be moved angularly in opposite

directions toward the closed ends of the body. When the cylinder is rotated, water will enter through the apertured sides of the ribs and through the apertured sides of the body and be forcibly delivered against the clothes therein. The clothes contacting with the ribs will be effectively agitated without danger of damage thereto. As the cylinder revolves, water in the washing machine will also pass through the apertures 10 into the bottom and into the cup 11, such water being sprayed through the apertures in the cup against the clothes in the cylinder, and it is thought that the foregoing description, when taken in connection with the drawings will fully set forth the construc-

tion, operation and advantages of the improvement to those skilled in the art to which such inventions relate.

Having described the invention, I claim:— 20

A clothes containing cylinder adapted for rotation in a washing machine, comprising a top, apertured sides, a bottom having a series of apertures therethrough, and a spray element surrounding said apertures, 25 oppositely inclined strips connected together in pairs and connected to the confronting edges of the top, sides and bottom, and one of each pair of strips having a central line of apertures therethrough.

In testimony whereof I affix my signature.

RICHARD M. COMISKEY.
